15 Claims. (Cl. 179—16)

This invention relates to telephone systems comprising a plurality of exchanges connected together by inductively coupled lines.

In such systems, it is usual for control current impulses to be transmitted over the speech lines of the exchanges in the form of direct current impulses and over the trunk lines in the form of alternating current impulses. Signal current impulses which indicate to the calling subscriber whether a line is idle or busy are sent over the speech lines and the trunk line to which they are connected. The trunk line and the speech lines are therefore normally connected together and are only disconnected for the transmission of control impulses. Rejecter circuits or bridge arrangements have, therefore, to be provided in the speech lines so as to prevent the transmission over the speech lines of the A. C. control impulses while allowing the transmission of signal and speech currents. Where amplifiers are provided, special balancing devices have to be provided to prevent their self-oscillation as they tend to howl if connected to the lines before the connection to the called subscriber is completed.

One object of the invention is to provide a telephone system in which the trunk lines are normally disconnected from the speech lines in the repeaters at their two ends.

Another object of the invention is to provide a telephone system in which a trunk line is connected to the speech lines by the action of automatic switch means when the called subscriber replies and in which the said connection is maintained only so long as the conditions in which conversation can take place persist.

Other objects of the invention will be made apparent in the following description made with reference to the accompanying drawings, in which:

Figure 1 shows by way of example the essential circuits of a repeater at the outgoing end of a trunk line, and

Figure 2 shows the essential circuits of a repeater at the incoming end of the same line.

In the arrangement illustrated in the drawings, the talking circuit remains open in the repeaters until the called subscriber replies and is opened when one of the subscribers hangs up his receiver. Any switch means responsive to currents of audible frequency in the repeaters cannot therefore be influenced by the direct action of speech currents during the making of a connection. One source of wrong connections in automatic systems is thus eliminated. If speech amplifiers are used, they are only put into the

circuit when the connection has been completed so that no special balancing arrangements are needed to guard against self-oscillation and howling of the amplifiers.

In order that signals may be transmitted to the calling subscriber while a connection is being set up, signal transmitters are provided on the calling side of the repeaters in the calling subscriber's exchange and are arranged so as to be controlled from the various selectors by impulses transmitted backwards over the trunk line.

The details of the various circuits required in such an arrangement will now be described together with an explanation of the operation of the system in the making of various different kinds of calls.

I. Trunk seized for an ordinary call

If the repeater U_{el} (Figure 1) is seized by a selector (not shown), the circuit is closed through the winding I of the relay A and the winding II of the relay C. Both relays respond. The relay A through its contacts a_1 and a_2 connects a source of alternating current to the line VL . An alternating current impulse is thus transmitted through the inductively connected repeater and the trunk line VL . The duration of this current impulse which is emitted automatically when the line is seized is limited by the response of the relay C, the contact c_1 of which short circuits the winding I of the relay A. When the relay A drops, a slow-to-respond relay Q is energised over the contacts c_7 and a_5 and, by means of its contact q_2 , switches in the slow-to-respond relay U . The contact u_4 then short circuits the relay Q . During the brief response of the relay Q , the winding I of the relay F, which is earthed, is connected by means of the contact q_1 to one wire of the speech line until reversal of the contact u_2 so as to receive the characteristic signal of the toll exchange which is given by causing current to flow through the wire in question when the toll exchange seizes the repeater.

If the first selecting current impulse arrives too early, i. e. before the relay Q has dropped, the relay B_{es} is energised in the circuit:

+ a-wire of the incoming line contacts g_2 , b_1 , winding II of relay A, contacts q_1 , u_2 , winding I of relay B_{es} , —.

A holding circuit is closed for the winding II of the relay B_{es} over the contacts c_2 and b_{es2} . The contact b_{es1} causes current to flow over the resistance W_{i2} and the b-wire of the incoming line. This causes the connection to be unmade in a selector nearer the calling subscriber. A

"busy" signal can be transmitted to the caller over the calling line.

The relay J in the repeater Ue2 (Figure 2) is energised by the short current impulse received by a signal receiver V4 which is tuned to audible frequency. The contact *jl* energises a relay AR and the contact *ar5* switches in the relay CR and, after the contact *cr3* has opened, the relay E. The contact *cr5* closes a holding circuit for the relays CR and E; the contact *cr2* earths the wire VL to the next selector, group selector or final selector LW. At the end of the current impulse, the relay AR drops. The slow acting relay QR is now energised over the contacts *cr1*, *ar3* and *ur4*, and by means of its contact *qr2* switches in the slow acting relay UR. The relay UR, by means of its contact *ur4*, opens the circuit for the relay QR so that the latter drops. The contact *qr3* switches the relay FR into a circuit dependent upon the contact *ar3*. After its energisation, the relay UR opens the circuit for the relay QR at the contact *ur4* and the circuit for the relay FR at the contact *ur3*. The relays QR and FR therefore drop.

25 II. Trunk seized for a toll call

When the repeater Ue1 (Figure 1) is seized by a trunk exchange the operations described above first of all take place. The relay F (Figure 1) is then, however, also energised because its winding I is connected to the a-wire for a short time over the contacts *b1*, *q1* and *u2*, as the seizing is accompanied by a flow of current through the a-wire. The following circuit is made:

+, winding I of relay F, contacts *u2*, *q1*, winding II of relay A, contacts *b1*, *g2*, a-wire . . .

The relays A and F respond in this circuit. The contact *f4* closes a holding circuit for the winding II of the relay F over the contact *c2*. The relay A necessarily transmits a further seizing current impulse to the line VL over the contacts *a1* and *a2*, the duration of this impulse being limited by the response of the relay U.

This second seizing current impulse energises the relay FR in the repeater Ue2 (Figure 2) over the contact *ar3*, the circuit being prepared by the contact *qr3* until energization of the relay UR. A holding circuit is closed for the relay FR over the contacts *cr1* and *fr2*. The contact *fr4* causes current to flow through the choke coil *Drot* and the contacts *fr4*, *tr4*, *qr1*, *tr3*, to the upper wire of the line leading to the next selector. A relay FA in this selector is thus energised so that the selector is set for toll connections.

55 III. Transmission of impulses

If the calling subscriber or the trunk toll exchange begins with the numerical selection for setting the group selectors and the final selector on to the desired subscriber's line, the a-wire of the speech line in the group selector (not shown) is earthed at each current impulse. The relay A in the repeater Ue1 (Figure 1) is thus energised each time in the following circuit:

+, . . . a-wire of the incoming line, contacts *g2*, *b1*, winding II of relay A, contact *q1*, resistance *W11*, -.

The relay A responds at each current impulse and energises the slow-to-attract relay B in the circuit:

+, contacts *c2*, *u3*, *a3*, relay B, resistance *W14*. The relay B responds at each current impulse, disconnects at the contact *b1* the winding II of the relay A from the a-wire for the remainder of the incoming current impulses and connects the wind-

ing III of the relay B to this a-wire in place of the winding II of the relay A. The relay A is thus energised only for a short time even when long current impulses are received. The source of alternating current is connected to the speech wire by the contacts *a1* and *a2* at each energisation. The current impulses are thus transmitted over the line VL to the signal receiver V4 of the repeater Ue2 (Figure 2) and thus to the relay J. The relay J responds at each current impulse and energises the relay AR. The contact *ar3* energises the relay VR, the release of which is delayed until after the reception of a current impulse train.

The current impulses are transmitted over the following path:

+, contacts *ur1*, *ar1*, *qr1*, *tr3*, upper wire of the line to the group or final selector.

In the case of long distance traffic, when the relays F (Figure 1) and FR (Figure 2) are energised, current is supplied to this wire over the choke coil *Drot* and the contacts *fr4*, *tr4*, *vr2*, *ar1*, *tr3* before and after each train of current impulses.

IV. All lines of the group selector or the desired subscriber's line are busy

If the group selector which has been set by the current impulses is unable to find a free line, a contact *du* is closed by the selector and the relay MR is thus energised in the repeater Ue2 in the circuit:

-, resistance *W14*, contact *du*, lower wire of the speech line, relay MR, contacts *e1*, *lr3*, winding II of the relay K, contact *tr8*, +.

Should the desired subscriber's line be engaged, the following circuit for the relay MR is closed in the final selector LW by the contact *ua1* which is opened during the setting of the final selector:

-, resistance *W14*, contacts *ua1*, *pa1*, lower wire of the speech line, relay MR, contacts *e1*, *lr3*, winding II of the relay K, contact *tr8*, +.

The resistance *W14* is so designed that in both cases only the relay MR and not the relay K responds. The contact *mr1* short circuits the slow acting relay NR which is energised when the repeater is seized by the contact *cr1*. The contact *mr2* energises the relay SR in the circuit:

+, contacts *cr5*, *k4*, *nr1*, *mr2*, winding II of the relay SR, -.

By means of its contacts *sr1*, *sr2*, the relay SR connects the source of alternating current to the line VL. The flow of alternating current is stopped after approximately 400 milliseconds by the dropping of the slow acting relay NR, the contact *nr1* of which opens the circuit for the relay SR.

In the repeater Ue1 (Figure 1), this long alternating current impulse is received by the signal receiver V1. The relay W is energised so that its contact *w1* energises a relay H, the contact *h2* of which energises a relay Y. The contact *y2* of the latter relay causes current to flow over the resistance *W12* and the contacts *t1*, *x1*, *y2*, *g3*, to the b-wire of the incoming speech line. This causes the connection to be unmade at one of the selectors. A "busy" signal can be transmitted to the calling subscriber.

V. Release of the connection before conversation

If, for example, the circuit through the c-line is interrupted in a selector in the calling exchange, the relay C (Figure 1) drops and, by means of its contact *c1*, opens the circuit for the slow acting relay U. The winding III of the re-

lay A is energised in a circuit running over the contacts *c4*, *u6*, *g6*, and the rest contact and wiper *b* of a transmitting switch SS so that the source of alternating current is connected to the line by the contacts *a1* and *a2*. Alternating current thus flows for the duration of the delay in release of the relay U. The holding circuits for the various relays of the repeater Ue1 are opened on release of the relay C so that these relays drop. On the other hand, the contact *a4* causes the slow acting relay V to be energised so that the contact *v1* opens the circuit through the *c*-wire and thus prevents further seizing of the repeater Ue1. When the relay U releases, the relay A is de-energised as, consequently, is the relay V. The repeater Ue1 can then be seized again. The long alternating current impulse is received in the repeater Ue2 (Figure 2) by the signal receiver V4. The relay J is energised and its contact *j1* switches in the relay AR. The latter short-circuits the relay CR over the contacts *ar5*, *e2*, *tr9*, which drops only upon reception of this long current impulse. Release of the relay CR causes the circuits of the various relays of the repeater Ue2 to be interrupted. The circuit for the line BL is also opened at the contact *cr2* so as to cause the following selectors to be released.

VI. Desired subscriber is free

If, however, the desired subscriber is free, the calling subscriber or the trunk exchange must receive the "free" or "idle" signal. Since the speech line is interrupted at the contacts *g2* and *g3* in the repeater Ue1 and at the contact *tr3* in the repeater Ue1, and is not connected up until the beginning of the conversation, i. e. until the desired subscriber has answered, the "free" signal must be transmitted back over the line.

If the called subscriber's line is disengaged, the testing relay PA in the final selector LW (Figure 2) responds, while a slow acting relay UA has not yet dropped. The following circuit is thus closed for a short time:

—, resistance *Wi16*, contacts *ua2*, *pa1*, lower wire of the speech line, relay MR, contacts *e1*, *tr3*, winding II of relay K, contact *tr8*, +.

The resistance *Wi16* is so designed that in this circuit only the relay MR responds and not the relay K. The relay MR energises the relay SR for a short time in the circuit:

+, contacts *cr5*, *k4*, *nr1*, *mr2*, winding II of the relay SR, —.

The source of alternating current is connected to the line VL by the contacts *sr1* and *sr2*. The length of the short alternating current impulse thus transmitted is limited by the release of the slow acting relay UA in the final selector LW, the circuit of which is interrupted in known manner when the final selector has been set.

The relay W in the repeater Ue1 (Figure 1) is energised by the short impulse received by the current receiver VI. Its contact *w1* energises the relay H and its contact *h2* energises the relay Y so that the contact *y2* causes current to flow over the resistance *Wi2* and the contacts *t1*, *x1*, *y2*, *g3* to the *b*-wire of the incoming line. At the end of the received current impulse, the relay W drops so that the relay H is de-energised and the relay X energised in the circuit:

+, contacts *c3*, *g9*, *h2*, *y4*, winding I of relay X, relay Y, —.

The contact *x1* now earths the *b*-wire of the incoming line. A "free" signal is thus sent to the calling subscriber from the selector on the calling

side or a "free" signal is switched in at the operator's position in the toll exchange. The relay T is thus energised over the contacts *c2*, *t2*, *x2*, *y3* and is locked in a circuit closed at *t3*.

VII. Response of the called subscriber in an ordinary call

If his line is free, the wanted subscriber is called automatically in the usual way if the connection has been made by an ordinary subscriber. When the called subscriber removes his receiver, the relay YA of the final selector LW (Figure 2) responds and energises a relay ZA which responds 60 milliseconds later and throws its contact *za1*. The following circuit remains closed during the 60 milliseconds delay in response of the relay ZA:

—, resistance *Wi15*, contacts *za1*, *ya1*, *ua2*, *pa1*, lower wire of the speech line, relay MR, contacts *e1*, *tr3*, winding II of relay K, contact *tr8*, +.

The relays MR and K are energised in this circuit. Contact *k4* prevents the winding II of the relay SR from being affected by the contact *mr2*. The contact *k1* closes a circuit for the slow-to-respond relay LR which responds after an interval of 80 milliseconds. Until the response of the relay LR, the relay SR is energised over the contacts *tr1*, *k2*, *tr2*. The contacts *sr1*, *sr2* send alternating current to the line. When the relay LR responds, the contact *tr1* switches in the relay TR. Consequently, the contact *tr6* closes a holding circuit for its relay TR; the contact *tr8* disconnects the winding II of the relay K and the relay MR; the contact *tr5* interrupts the circuit for the winding I of the relay K and for the relay LR; the contact *tr11* interrupts the circuit for the winding I of the relay SR so that this relay cannot be energised when the relays K and LR drop successively on opening of the contact *za1*; the contact *tr3* switches in the speech line; the contacts *tr1* and *tr2* remove the short circuit for the speech amplifier V3; the contact *tr9* opens so that the short circuit for the relay CR is controlled by the contact *rrs2* of a double armature relay RR which, as will be described below, can be energised only on receipt of a certain current impulse combination.

In the outgoing repeater Ue1 (Figure 1), a current impulse having a duration of 80 milliseconds is received by the relay W which energises the relay H. The contact *h2* interrupts the circuit for relay Y and closes a circuit through the winding II of the relay X. At the end of the current impulse, this circuit is interrupted at the contact *h2* and the relay X drops.

The relay G is now energised in the circuit: +, contacts *c2*, *t2*, *rs1*, *x2*, relay G, —.

The contacts *g2* and *g3* switch in the speech line. The contacts *g10* and *g11* remove the short circuit for the amplifier V2. The contact *g4* prevents the relay H, and the contact *g9* the relays X and Y from being switched in again. The contact *g6* prepares the energisation of the relay L and the contact *g1* the energisation of the relays O, P and R.

VIII. Response of the called subscriber in a toll connection

If the connection has been made by a toll operator, the relays F (Figure 1), FR (Figure 2) and the final selector relay FA are energised. When the called subscriber replies, current is caused to flow continuously to the *b*-wire of the speech line over the closed contact *fal* independently of the contact *za1*. In the repeater Ue2, the relays K, LR and TR are also energised in the manner de-

scribed and an alternating current impulse of 80 milliseconds duration is sent back through the line. The relay G in the repeater Ue1 is thereby energised in the manner described and switches 5 in the speech line. Also, current is caused to flow to the b-wire of the incoming line over the choke coil Dro and the contacts f1, g1, so that a signal is given to the operator in the toll exchange.

IX. Cutting off in an ordinary connection

10 Owing to the speech lines being switched in at the contacts g2, g3, in the repeater Ue1, when the called subscriber replies, the signal receivers V1 and V4 which are tuned to audible frequency and thus the receiving relays W (Figure 1) and J (Figure 2) are acted upon by the speech currents. These may cause the relays to be operated in an unforeseen manner and it is necessary to provide against the possibility of the speech transmission 15 being thereby interrupted or other undesired operations such as cutting off of the connection occurring. On the other hand, it must still be possible to cut off the connection when one of the subscribers replaces his receiver. For the purpose of cutting off the connection after a conversation has been started, a special current impulse combination has to be emitted.

If the circuit through the c-wire of the incoming line is interrupted, for example, when the 30 calling subscriber replaces his receiver, the relay C (Figure 1) drops and the contact c7 opens the circuit of the slow-acting relay U. As the relay G was energised at the beginning of the conversation, the following circuit for the relays L, S is now closed until the relay U releases:

contact s2, relay S, -.
+, contacts c4, u6, g6
rest position and wiper a of the transmitting switch SS, contact a, relay L, -.

40 The relay S is connected in a holding circuit by the contacts s2 and h3. The contact l1 switches in the stepping magnet D of the transmitting switch SS; the contact s1 interrupts the circuit through the c-wire of the incoming line 45 and thereby prevents the repeater Ue1 from being seized again; the contact c2 disconnects the slow-to-release relay G and the relay T. The speech line is thus interrupted and the receiving relays are removed from the influence of the calling 50 subscriber's speech currents. The relay L and the magnet D of the transmitting switch SS operate alternately. The magnet D is therefore energised intermittently and steps the wipers a, b of the transmitter switch SS. The first step brings the wiper b on to an earthed contact. The winding III of the relay A remains energised for 55 50 milliseconds. When the wiper comes on to the second contact, the relay A is disconnected from earth for 50 milliseconds and releases. By connecting a number of successive contacts to earth, the relay A can be held energised for correspondingly longer periods, for example 300 milliseconds. The energisation of the relay A and, therefore, 60 the emission of alternating current by the contacts a1 and a2 over the line VL are thus controlled by the wiring of the contact bank wiped over by the wiper b. Let us assume that the current impulse combination - - - - is sent out. The 65 relay J in the repeater Ue2 responds rhythmically with the current impulses received by the signal receiver V4. The contact j1 energises the relay AR and the contact ar3 switches in the relay VR which, being slow-acting, remains energised for 70 the duration of receipt of the current impulse 75

combination. The contact ar7 controls a device comprising the two-step relays OR, PR, RR and WR. The contacts of these relays which are actuated at the first step are marked * in the drawings. After receipt of the first current impulse, the relay OR is energised and makes its first step in the circuit:

-, winding 1 of relay OR, contacts ar7, ur5, vr3, tr10, nr2, rrs6, yrl, cr4, +.

On receipt of the second current impulse, the 10 relay OR makes its second step and during the pause following the receipt of the second current impulse, the relay PR makes its first step. On receipt of the third current impulse, the relay PR makes its second step and during the pause 15 following the receipt of the third impulse, the relay RR makes its first step. On receipt of the last (fourth) current impulse, the relay RR makes its second step. When making its second step, each of the relays OR, PR and RR throws its 20 contact ors5, prs4, orrs5 and is locked in a circuit which runs through the contacts ur5, vr3, tr10, nr2, xr2, yrl and cr4. The relay VR is a supervisory relay, the function of which is to determine whether the current impulses arrive at the 25 correct time intervals. If no further current impulse is received 100 milliseconds after the reception of an impulse, the relay VR drops and 30 interrupts the locking circuit for the relays OR, PR and RR at its contact vr3. The supervisory relay NR checks the length of the first current impulse. If it lasts longer than 100 milliseconds, the relay NR drops and opens its contact nr2. On reception of a first current impulse of the prescribed length, the relay NR is held energised by 35 the contact or12. The exact length of the second current impulse is supervised by the relay UR which, on receipt of this current impulse, is short circuited by the contacts pr11, and ors1. If a current impulse lasting more than 100 milliseconds is received, the relay UR drops and opens its contact ur5. The length of the third current impulse is supervised by a relay XR which has a release delay of 200 milliseconds. This relay XR is short circuited by the contact prs6 on receipt 40 of the third current impulse which lasts 300 milliseconds. It is only when the relay XR drops and closes its contact xr2 that the locking circuit for the relays OR, PR and RR is not interrupted on receipt of the fourth current impulse. The duration of the fourth current impulse is supervised 45 by the relays CR and YR. On receipt of the fourth current impulse which lasts 300 milliseconds, the relay YR is short circuited by the contact rrs7. The relay YR has a release delay of 50 55 200 milliseconds. If the current impulse is so short that it does not drop, further current impulses are at once received and the relay WR is energised and makes its two steps and by means of the contact wrs4 interrupts the locking circuit for the relays OR, PR and RR. On receipt of the fourth current impulse, the relay CR is short circuited by the contact rrs2 and drops provided the current impulse has the prescribed 60 length of 300 milliseconds. As the relay RR can only be energised on receipt of the fourth current impulse if the preceding short and long current impulses have been received in the right sequence, the release takes place only if the length of the received current impulse combination - - - - 65 corresponds exactly to the prescribed lengths of the various current impulses and pauses. On receipt of the current impulse combination, two things can occur:

(1) If the correct current impulse combina- 75

tion has been received, the relay CR in the repeater Ue2 is released by the fourth current impulse. The relays UR, TR, NR and E are thus deprived of current. The contact *cr2* interrupts the circuit through the line BL and thus brings about the release of the succeeding selector LW (Figure 2). The line VL must be prevented from being seized again until this selector has been restored to the normal position. By means of the contact *k* of the selector LW which is open only in the normal position of the selector, the following circuit is closed:

—, resistance *W17*, contacts *k*, *e1*, *lr3*, winding II of relay K, contact *tr8*, +.

The relay K responds and, by means of its contact *k2*, energises the winding I of the relay SR so that the source of alternating current is connected to the line. The slow-to-attract relay LR is switched in by the contact *k1* and responds 80 milliseconds later and, by means of its contact *lr2*, interrupts the circuit for the relay SR. The alternating current impulse of 80 milliseconds duration which is emitted by the relay SR is received in the repeater Ue1 (Figure 1) by the relay W provided that the relay V which has been energised during the emission of the current impulse combination has not yet dropped and by means of its contact *v1* holds the seizing circuit through the c-wire of the incoming line open. The relay W energises the relay H through its contact *w1* and the latter relay through its contact *h2* switches in the relay Y. Upon receipt of the short current impulse, the relay Y is locked in a circuit closed at its contact *y4*. The relay Y, by means of its contact *y1*, interrupts the circuit through the c-wire even after the relay V has released. At the same time, the opening of the contact *h3* deprives the relay S of current. When the selector LW returns to the normal position, the circuit for the relay K is interrupted by the contact *k*. The relay SR is again switched in for the duration of the delay in release of the relay LR by the contacts *tr1*, *k2*, *lr2*. The contacts *sr1* and *sr2* again connect the source of alternating current to the line for the emission of a short current impulse. This current impulse energises the relays W and H in the repeater Ue1. The circuit for the relays X and Y is interrupted by the contact *h2*. The relay Y drops and, by means of its contact *y1*, preparatorily closes the seizing circuit through the c-wire of the incoming line. The repeater Ue1 can now again be seized.

(2) If the correct current impulse combination is not received, for example, because the called subscriber has spoken in the meantime and has operated the relay W by means of the alternating speech currents, the relay CR in the repeater Ue2 remains energised and the short alternating current impulse is not emitted. The relay S in the repeater Ue1 also remains energised. The relay L is switched in by the contacts *s3*, *v4* and the wiper *a* of the transmitting switch SS which, in the meantime, has returned to its normal position, and this relay, together with the magnet D in the manner described, again steps the transmitting switch SS. A new current impulse combination is thus emitted. This procedure is repeated until the relay S has been caused to drop by the backwardly transmitted alternating current impulse. An alarm signal can be sent over the contact *s5* and the line AL if the relay S remains energised for an excessively long time.

It may be desirable in many cases not to release the connecting devices immediately the call-

ing subscriber replaces his receiver, for example, if at the end of the conversation, current impulses are to be transmitted from the called subscriber's exchange to the calling subscriber's exchange which characterise the zone value of the connection from which the charge is to be calculated. In such cases, when the calling subscriber replaces his receiver, the circuit is not interrupted by way of the c-wire of the incoming line but a circuit is closed through the a-wire of this line by which a relay RA in the repeater Ue1 is energised so that the relay G de-energises and switches in the transmitting switch for the emission of a special current impulse.

This current impulse does not then bring about the de-energisation of the relay CR in the repeater Ue2, (Figure 2), but de-energises the relay TR which interrupts the speech line. In this way, the speech line is restored to the condition which exists during the setting. The relays W and J can no longer be influenced by speech currents and any desired switching operations may be transmitted in both directions over the line. The release is effected later as described under the foregoing sub-heading V.

X. Clearing by the called subscriber

When a called subscriber who has been connected by the toll exchange replaces his receiver, the relay YA of the final selector LW (Figure 2) releases again and by means of its contact *ya1* opens the circuit for the relay K. The relay LR is switched out by the contact *k1* and does not drop until 80 milliseconds later. The relay BR is energised in the circuit:

+, contacts *tr13*, *k5*, *lr4*, normal position and wiper *b* of the transmitter switch SSR, contact *dr*, relay BR, —.

The contact *br1* switches in the stepping magnet Dr of the transmitting switch SSR. When the relay LR releases, the contact *lr1* interrupts the circuit for the relay TR which again interrupts the speech line. The relay BR and the rotary magnet Dr of the transmitter switch SSR operate alternately so that the wipers *a* and *b* are stepped on. The winding II of the relay SR connected to the wiper *a* of the transmitter switch SSR is energised each time the wiper encounters an earthed contact and by means of the contacts *sr1* and *sr2* transmits an alternating current impulse to the line VL. The current impulse combination — — . . is thus, for example, sent out.

The relay W in the repeater Ue1 (Figure 1) responds rhythmically with the received current impulse combination. The contact *w1* energises the relay H in a circuit running through the contact *f3* and the contact *h1* energises the relay V which does not drop unless no current impulses are received over a considerable period of time. The contact *h4* controls a device comprising the two-step relays O, P and R. The contacts of these relays which are actuated at the first step are marked * in the drawings. In the pause after the receipt of the first current impulse, the relay O makes its first step in the circuit:

—, winding I of relay O, contacts *os1*, *h4*, *m2*, *v5*, *p15*, *ps6*, *g7*, +.

On receipt of the second current impulse, the relay O makes its second step and during the second pause, the relay P makes its first step. The relays O, P and R are thus successively energised and are each locked in a circuit closed at

the second step. The contact *rs1* interrupts the circuit for the relay *G*. The correct length of the pause between the various current impulses is supervised by the relay *V* which has a delayed release of 100 milliseconds. The contact *v5* interrupts the circuit for the relays *O*, *P* and *R*. The length of the first current impulse is supervised by the relay *M* which, on receipt of this impulse, is short circuited by the contacts *h5*, *g8* and drops after 200 milliseconds. The length of the second current impulse is supervised by the relay *N* which is short circuited on receipt of this impulse by the contacts *h5*, *os8* and drops after 200 milliseconds. The length of the third current impulse is supervised by the relay *M* which is energised again by the contact *os7* after receipt of the first current impulse. If the third current impulse is too long, the relay *M* drops and its contact *m3* interrupts the circuit for the relays *O*, *P* and *R*. The duration of the last current impulse is supervised by relays *G* and *M*. The relay *G* is de-energised only if the length of the received current impulse combination corresponds exactly to the correct duration of the various current impulses and pauses. The contacts *g2* and *g3* interrupt the speech line and thus destroy the conversation conditions in the repeater *Ue1*. The contact *g1* disconnects the *b*-wire of the incoming line from the source of current. In this way, a signal is given in the trunk exchange which indicates that the called subscriber has replaced his receiver. The trunk exchange operator can now send out a current impulse which is transmitted over the line *VL* as a setting current impulse and which influences means provided in the final selector for switching in a device for transmitting ringing current periodically to the desired subscriber.

If, for any reason, the called subscriber again removes his receiver, the speech line is again switched through as at the beginning of the conversation.

XI. Connection of the toll operator to an engaged subscriber

If the desired subscriber's line has been seized from the toll exchange, the operator, by emitting through the *a*-wire of the line a current impulse which is transmitted over the line *VL* as a setting current impulse, can cause the final selector *LW* (Figure 2) to be connected to the engaged subscriber's line. The speech lines in the repeaters *Ue1*, *Ue2* are then switched in as at the beginning of a conversation.

XII. Severing of a local connection by the toll operator

If the toll operator now wishes to sever the existing connection to the desired subscriber, she sends a fresh current impulse through the *a*-wire of the incoming line (Figure 1). This current impulse is received by the winding *II* of the relay *A* which is connected to the *a*-wire by way of the contacts *f2* and *g2*. A current impulse is sent out by the contacts *a1* and *a2*. At the same time, the relay *L* is energised by the contacts *a6*, *f5*, *g6* and switches in the current impulse combination transmitter switch *SS*, so that the current impulse combination . . . . . is emitted by the periodical energisation of the winding *III* of the relay *A*. The energisation of the winding *II* of the relay *A* which causes the switching in of the impulse combination transmitter does not disturb the correct emission of the impulse combination; the first impulse is

somewhat lengthened, but only to such an extent that the relays *OR*, *PR*, *RR* of the repeater *Ue2* (Figure 2) can still correctly respond to the received impulse combination as described above. The relay *RR* in the repeater *Ue2* is again energised in the second stage on receipt of this current impulse combination. Since, however, relay *FR* is energised when a connection is made by the toll exchange, it is not the relay *CR* but the relay *TR* which is now short circuited and cut out. When the relay *TR* releases, a current impulse is transmitted by the contacts *ur1*, *ar1*, *qr1*, *tr3* to the final selector *LW* and causes the existing connection to be interrupted therein. The relay *YA* then responds again so that the relays *K* and *LR* are energised. The contact *tr1* switches in the relay *TR* so that the speech lines in the repeater *Ue2* are again switched through.

XIII. Release of a toll connection

When the called subscriber has cleared, the speech lines are disconnected by de-energisation of the relays *G* and *TR* as described under the foregoing sub-heading *X*. To release the connection, the toll operator opens the circuit for the relay *C* (Figure 1) in the known manner. For the duration of the delay in release of the relay *A*, a long A. C. impulse is sent through the line *VL* in the repeater *Ue2*, the relays *CR* and *E* (Figure 2) are de-energised and the circuit for the line *VL* is opened so as to cause the connector *LW* to be cleared (as described under the foregoing sub-heading *V*). If the connection is made through a number of exchanges and a number of lines, the release of the devices such as the relays *G* and *R* which serve to switch through the speech lines may be effected simultaneously in all repeaters on receipt of one current impulse combination. If, on the other hand, those devices are to be released stage by stage, from exchange to exchange, then different current impulse combinations must be transmitted successively through the various lines.

The devices for the transmission and the reception of such current impulse combinations may be constructed in any desired manner. Synchronously running distributors may also be employed such as are known in telegraph arrangements. In this way, combinations of a number of current impulses of equal length or of current pauses may be transmitted and be distributed by the rotary distributor to appropriate receiving devices which evaluate them by means of pyramidal arranged contacts.

I claim:

1. A telephone installation comprising a plurality of exchanges, trunk lines between said exchanges, repeaters inductively connected to the ends of said trunk lines, at least one calling subscriber's line, at least one called subscriber's line, a speech circuit in each of said repeaters, switch means associated with said repeaters, means operated as a consequence of said called subscriber replying for making said switch means operative to switch in said speech circuits and means operated as a consequence of one of said subscribers' replacing his receiver for making said switch means operative to disconnect said speech circuits.

2. A telephone installation according to claim 1, comprising also devices associated with said repeaters for the transmission of alternating current audible frequency impulses, devices associated with said repeaters for the reception of said alternating current impulses, switch means

associated with said repeaters and controlled by said current impulse receiving devices, means for preventing said switch means from being operated by said receiving devices, said last mentioned means being controlled by said means which are operated as a consequence of the removal of the called subscriber's receiver.

3. A telephone installation comprising a plurality of exchanges, trunk lines between said exchanges, inductively connected repeaters at the ends of said trunk lines, at least one calling and one called subscriber's line, a speech circuit in each of said repeaters, said speech circuit comprising a point of interruption, switch means associated with said repeaters for switching in said speech circuit, means made operative on removal of said called subscriber's receiver for making said switch means operative to switch in said speech circuits, current impulse combination transmitting devices associated with said repeaters and adapted to be prepared by said switching in switch means, and current impulse combination receiving devices associated with said repeaters and adapted to be made inoperative by said switching in switch means.

4. A telephone installation comprising a plurality of exchanges, trunk lines between said exchanges, inductively connected repeaters at the ends of said trunk lines, at least one calling subscriber's line and one called subscriber's line, each of said repeaters comprising a speech circuit including a point of interruption, devices adapted to allow the passage of signal currents bridging said points of interruption, switch means associated with said repeaters for switching in said speech circuits, means made operative when said called subscriber removes his receiver for making said switch means operative to switch in said speech circuits and means made operative when one of said subscribers replaces his receiver for making said switch means operative to disconnect said speech circuits.

5. A telephone installation comprising a plurality of exchanges, trunk lines between said exchanges, inductively connected repeaters at the ends of said trunk lines, at least one calling subscriber connected to a calling exchange, at least one called subscriber connected to a called exchange, switch devices associated with said calling exchange for the emission of signal currents to said calling subscriber, switch devices associated with said called exchange for the transmission of backward signals, said switch devices associated with the calling exchange being operated by said backward signals, switch means in each of said repeaters for the emission of current impulses and switch means in each of said repeaters for the reception of current impulses, a speech circuit having points of interruption in each of said repeaters and switch means in each of said repeaters for switching in said speech circuit, means operated when said called subscriber's receiver is removed for making said switch means operative to switch in said speech circuits and means operated on replacement of the receiver of one of said subscribers for making said switch means operative to disconnect said speech circuits.

6. A telephone system comprising a plurality of exchanges, a plurality of subscribers' lines connected to said exchanges, trunk lines connecting said exchanges, repeaters arranged at the two ends of each of said trunk lines, speech lines in said exchanges connected to said repeaters, the connection in said repeaters of said speech lines

and said trunk lines being normally open, switch means in said repeaters automatically operated when a called subscriber replies for connecting a speech line to a trunk line and means for maintaining said connection only while talking conditions subsist.

7. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, automatic switches associated with said connecting devices and differently operated when said called subscriber replies and when he hangs up his receiver, each of said repeaters comprising normally open switch means between the trunk line and the associated speech line, means controlled by said automatic switches when the called subscriber replies for actuating said switch means so as to close the connection of said trunk line to said speech line and means for maintaining said connection only while talking conditions subsist.

8. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, each repeater comprising an alternating current receiving relay connected to said trunk line, means for transmitting alternating current impulses over said trunk line, circuits controlled by said alternating current receiving relay, normally open switch means between said trunk line and the associated speech line, a relay for closing said switch means only when the called subscriber replies and means controlled by said relay for making said circuits controlled by said alternating current receiving relay ineffective.

9. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, each repeater comprising a receiving relay connected to said trunk line, means for transmitting impulses over said trunk line, normally open switch means arranged between said trunk line and the associated speech line, a relay for closing said switch means only when the called subscriber replies, a switching device operable only on receipt of a predetermined train of impulses and means controlled by said last-mentioned relay for controlling said switching device by said receiving relay.

10. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, each repeater comprising normally open switch means arranged between said trunk line and the associated speech line, a

75 75

- relay actuated on reply by the called subscriber for closing said switch means, a locking circuit for said closing relay, a receiving relay connected to said trunk line, a switching device operable only on the receipt of a predetermined train of impulses and switched in by said closing relay so as to be operated by said receiving relay and means actuated by said switching device for interrupting said locking circuit.
- 10 11. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, speech amplifiers arranged at the ends of said trunk line, each repeater comprising normally open switch means situated between the trunk line and the associated speech line, a relay actuated on reply by the called subscriber for closing said switch means, means controlled by said relay for switching said amplifiers into action, means effective only while talking conditions subsist between the calling and the called subscribers for holding said closing relay energised.
- 15 12. A telephone system comprising in combination at least one calling exchange having a speech line, a calling subscriber connected to said calling exchange, at least one called exchange having connecting devices and a speech line, a called subscriber connected to said called exchange, at least one trunk line connecting said exchanges, repeaters arranged at the two ends of said trunk line, each repeater comprising normally open switch means situated between the trunk line and the associated speech line, a relay actuated on reply by the called subscriber
- 20 for closing said switch means, a switching device operable only on the receipt of a predetermined train of impulses, a receiving relay connected to said trunk line, means controlled by said closing relay on its actuation for switching said switching device so as to be actuated by said receiving relay and an impulse emitting device for emitting a predetermined train of impulses prepared by said closing relay on its actuation.
- 25 13. A telephone system as claimed in claim 12, in which said repeater at the incoming end of the trunk line comprises also means actuated on the replacement of the called subscriber for switching said impulse emitting device into action.
- 30 14. A telephone system as claimed in claim 12, in which said repeater at the outgoing end of the trunk line comprises also means connected to the speech line of the calling exchange and actuated by a control current received over said speech line when talking conditions exist between said subscribers for switching said impulse emitting means into action.
- 35 15. A telephone installation comprising a plurality of exchanges, trunk lines between said exchanges, repeaters inductively connected to the ends of said trunk lines, at least one calling subscriber's line, at least one called subscriber's line, speech amplifying means associated with said repeaters, a speech circuit in each of said repeaters, switch means associated with said repeaters, means operated on said called subscriber removing his receiver for making said switch means operative to switch in said speech circuits and said speech amplifying means and means operated when one of said two subscribers replaces his receiver for making said switch means operative to disconnect said speech circuits and said speech amplifying means.
